UNITED STATES PATENT OFFICE

2,513,057

CONTINUOUS AFTERTREATMENT OF RAYON

Hans Alwin Schrenk, Arnhem, Netherlands, assignor to American Enka Corporation, Enka, N. C., a corporation of Delaware

Application December 4, 1946, Serial No. 713,905
In Germany July 14, 1941

Section 1, Public Law 690, August 8, 1946
Patent expires July 14, 1961

1 Claim. (Cl. 8—151.2)

1

This invention relates to the treatment of rayon and is more particularly concerned with a method and apparatus for the continuous wet treatment of a plurality of rayon yarns moving between a point of extrusion and a point of collection.

In the aftertreatment of rayon yarns, each composed of a multiplicity of filaments, it is known to pass the same in a continuous operation through a series of treating tanks wherein the yarns are guided beneath the surface of liquid in each tank and parallel to the surface thereof. Two types of guiding rollers are normally employed for this purpose, one type being located above the tanks for guiding the yarns from one tank to the other, and the other type being wholly or partially immersed in the liquid of the tanks for guiding the yarns through the treating baths.

It has now been determined that it is not necessary to drive all of the rollers, because if the rollers located above the tanks are driven, the rollers immersed in the baths can be freely rotatable as the yarns passing thereover will rotate the same. In order to maintain the yarns in parallel relationship during their passage through the baths, it is preferable to provide the rollers above the baths with parallel grooves, whereas the rollers immersed in the baths can have a smooth surface.

In the foregoing process, it is necessary that the individual filaments of each yarn are sufficiently separated from each other so that the treating liquid can adequately penetrate them during the relatively short period in which the filaments are in the baths. On the other hand, the individual filaments should not be separated too much because then the filaments of the adjacent, moving yarns may become entangled.

The separation of the filaments is dependent upon the distance they travel through the bath, the speed at which they travel through the bath and the tension on the filaments which has been imposed in front of the first roller.

It is therefore an object of this invention to overcome the foregoing difficulties and to provide a method and apparatus for the aftertreatment of multi-filament rayon yarns wherein the yarns are subjected to adequate aftertreatment in passage through baths of relatively short physical length.

It is contemplated, according to this invention, to separate the component filaments of a yarn so as to cause the yarn to assume ribbon form during its passage through an aftertreatment bath, whereby the individual filaments may be

2

better contacted with the aftertreating liquid.

It is a further object of this invention to provide apparatus for feeding yarn to, and withdrawing yarn from, baths of aftertreating liquid in such manner that the threads will be properly spread into ribbon form in their passage through the aftertreating liquid in order to effect sufficient penetration of the treating liquid without entanglement.

10 Other objects and advantages of this invention will be apparent upon consideration of the following detailed description of a preferred embodiment thereof in conjunction with the annexed drawings wherein:

15 Figure 1 is a diagrammatic view in vertical section of apparatus constructed in accordance with the present invention; and

Figure 2 is a fragmentary view in plan illustrating a typical driving connection for the apparatus shown in Figure 1.

20 Referring now in greater detail to Figure 1, the numerals 10, 11 and 12 designate containers for the reception of aftertreating liquids 13, 14 and 15 which may be water, sodium sulphide and water respectively. The yarn issuing from a spinning position, not shown, is delivered to the container 10 by a driven roller 16. The yarn passes from driven roller 16 through aftertreating liquid 13. In container 10 there are located two freely rotatable guiding rollers 17 and 18 around which the thread passes in its path of travel through liquid 13. From the roller 18 the yarn is withdrawn from the container 10 by a driven roller 19 and roller 20, in addition to withdrawing the yarn from the container 10, also feeds it into container 11. In passing through container 11 the yarn is guided by rollers 21 and 22 corresponding in structure and function to rollers 17 and 18. The yarn is withdrawn from the container 11 by a driven roller 22 corresponding in structure and function to the roller 19. The apparatus for guiding the yarn through the container 12 corresponds to that described in connection with container 11 and includes freely rotatable rollers 23 and 24. The aftertreated yarn is withdrawn from the container 12 by a driven roller 25.

25 Upon reference to Figure 2 it will be noted that all of the rollers 16, 19, 22 and 25 are driven from a common power shaft 26. Shaft 26 is connected to any conventional driving apparatus and is driven at such a speed that it will drive the rollers 19, 22, and 25 at a speed approximating the spinning speed. To this end, shaft 26 is provided with bevel gears 27, 28 and 29 which mesh

with bevel gears 30, 31 and 32 respectively to drive rollers 19, 22 and 25 respectively, all at the same speed. Shaft 26 is also provided with a bevel gear 33 which meshes with a bevel gear 34 which drives one side of a change speed transmission 35 of any conventional design such as, for example, a P. I. V. transmission which is a standard link belt variable speed drive mechanism. The letters P. I. V. stand for "positive infinitely variable." The output side of the transmission 35 is connected through a shaft 36 to the driven roller 16.

It has been discovered, as an important part of this invention, that if the roller which feeds the yarn to the after-treating liquid is driven at a different speed from the rollers which withdraw the yarn from that liquid, it is possible to control the degree of separation of the component filaments of the yarn in such a way as to best expose them for reaction with the after-treating liquid. It is for this reason that the transmission 35 is provided, for by the use of this transmission, it is possible to drive the roller 16 at a speed which is different from the speeds of rollers 19, 22 and 25. The range of variation between the speed of roller 16 and the speed of the other rollers can be very small. It is found that upon increase in the speed of the roller 16 relative to the other rollers, filament separation is increased while a decrease in the speed of the roller 16 relative to the other rollers, results in a decrease in filament separation. The phenomenon of filament separation of the sort described is not fully understood, but is believed to result from the elasticity of the wet threads.

Tests have shown that adequate filament separation in all of the treating baths 13, 14 and 15 will be attained, for example, if each bath is 45 centimeters in length, and the peripheral speed of the roller 16 is 60 meters per minute, and is adjusted to exceed by approximately one percent the peripheral speed of the rollers 19, 22 and 25.

While the specific description has reference to the propulsion of a single yarn through the various aftertreating baths, it is contemplated that the rollers 16, 19, 22 and 25 be provided with grooves 16', 19', 22' and 25', respectively, and be of sufficient axial length so that a plurality of yarns moving in parallel relationship may be accommodated thereby for simultaneous after-treatment.

It can now be seen that by practicing the method here disclosed, and by using the apparatus here described, it is possible to adequately control filament separation in the passage of freshly spun yarns through aftertreating baths with the re-

sult that the aftertreatment can be accurately controlled and baths of reduced physical length may be satisfactorily employed. It will, of course, be understood that variations from the disclosed method and apparatus may be made and that the foregoing description is exemplary and is not intended to be exhaustive of the modifications that are possible within the scope of the invention.

10. What is claimed is:

A method of aftertreating freshly spun substantially untwisted multi-filament rayon yarns which comprises feeding a plurality of such yarns continuously in parallel relationship into a stationary, common bath at a constant speed, passing the yarns from said bath and into, through and out of additional stationary and common baths while maintaining the yarns out of contact with each other and exposed on all sides to the bath liquid and in parallel relation to each other, withdrawing the yarns from the last bath at a constant speed lower than the speed of delivery thereof to the first bath, and applying a uniform propulsive force to each of the yarns between adjacent baths under slippage permissive conditions, the propulsive force applied to the yarns between the respective baths being at substantially the same speed as the rate of yarn withdrawal from the last bath, whereby the yarns are passed through at least some of the baths at a rate greater than the rate of application of propulsive force thereto with resultant adjustment of the individual yarns due to inherent shrinkage and slip with respect to the propulsive force applied thereto and resultant passage of the yarns through the baths in relaxed condition such that the drag on the yarn through the baths separates the filaments of the respective yarns sufficient to permit ready access of bath liquids thereto.
